ATTORNEY.

UNITED STATES PATENT OFFICE.

LOUIS DUBRULLE, OF PARIS, FRANCE.

LUBRICATING-OIL DISTRIBUTER.

No. 900,154.

Specification of Letters Patent.

Patented Oct. 6, 1908.

Application filed January 2, 1907. Serial No. 350,505.

To all whom it may concern:

Be it known that I, LOUIS DUBRULLE, citizen of France, residing at Paris, in the said Republic, have invented new and useful Improvements in Lubricating-Oil Distributers, (for which I have obtained a patent in France, No. 363,123, bearing date February 10, 1906; in Italy, No. 231171, May 31, 1906, and in England, No. 17,168, July 30, 1906,) of which the following is a specification.

In lubricating oil distributers used hitherto for motor cars, the oil is forced to the distributor by putting it under pressure in the reservoir, either by means of a portion of the 15 exhaust gases from the motor or by means of a small air pump. Sometimes the oil is supplied to the distributor by an independent pump controlled by the motor.

The present invention relates to a lubricating oil distributor that is independent of the reservoir, which may be placed at any part of the vehicle. The distributor is controlled by the motor and draws oil directly 20 from the reservoir, transmitting this oil under pressure to the diverse parts to be lubricated.

The apparatus consists, essentially, of a primary pump feeding a distributor and returning the excess of oil to a feeding tank, 30 and of secondary pumps sending the oil from dropping tubes into corresponding conduits which lead to the points to be lubricated, the piston of the primary pump and those of the secondary pumps being mounted on the 35 same rod, to which reciprocating movement is contributed by any suitable means.

The invention is illustrated in the accompanying drawings.

Figure 1 is a longitudinal vertical section, 40 on line *a*—*b* of Fig. 2 or Fig. 3, of an apparatus for distributing under high pressure oil drawn from a separate reservoir. Fig. 2 is a transverse section on line *c*—*d* of Fig. 1. Fig. 3 is a longitudinal horizontal section on 45 line *e*—*f* of Fig. 1.

The apparatus here shown comprises three dropping tubes, although the number may be varied as may be necessary, the distributor being extended for the purpose.

The apparatus consists of a distributor body 3 having a cylindrical bore 4 subdivided into a number of small cylinders, 6, by corks or partitions 5. In each of these small cylinders works a piston 7, the pistons 7 and 50 the cylinders, 6, constituting a plurality of

secondary pumps. The several pistons are fixed to a rod, 10, common to them all. The end of this rod is connected with a bell crank lever 1 centered on a bracket 23 and pivoted at its end 2 to a rod to which a reciprocating movement is given by a cam, or the like, keyed on one of the reducing shafts of the motor.

The oil is pumped by the piston 8 of the suction and force pump and through the 65 passages of the casting 9, this piston being also mounted on the rod 10. The pump 9 is connected by an inlet pipe 13 with the oil reservoir, which may be at any part of the vehicle. The pump forces the oil through 70 passage 12 into a compartment or header, 11, whence it flows down the dropping-tubes or sight feeds 14, at a rate controlled by the needle valves 15, into the compartments 20 having glazed fronts 21, through which the 75 proper working of the dropping-tubes may be observed. From these compartments the oil flows through ducts, 16, to the respective cylinders or secondary pumps 6. The latter communicate by passages 17 with the 80 discharge pipes 18; the said passages 17 may be closed by spring pressed balls 19 which act as valves for the pumps. Excess of oil is returned, from the header, 11, to the reservoir through a duct 24 communicating with 85 the discharge pipe 25. The controlling lever 1 and with it the rod 10 carrying the pistons is returned by the spring 22.

The apparatus operates as follows:—The motor having been started, the controlling 90 rod, operated by the cam or eccentric, draws down the lever 1 which is then returned by the spring 22, so that the rod 10, with the three pistons 7 and the main piston 8, receives a reciprocating movement. In consequence, the primary pump 9 sucks oil from the reservoir and forces it to the dropping-tubes or sight feeds 14, which distribute it in the desired quantity, under control of the needle valve 15, to each of the pump cylinders 6, the oil thus distributed drop by drop or even in fine streams, is forced by the secondary pistons 7 to the parts to be lubricated. The excess of oil brought to the distributor by the main pump 9 but not distributed by 100 the dropping-tubes, is returned to the reservoir by the pipe 25.

I claim:

In a lubricator, a primary pump, a plurality of secondary pumps, and discharge pipes 110

therefor, a rod on which all the pistons of the aforesaid pumps are mounted, a header provided with sight feeds for the secondary pumps, an inlet pipe and a discharge pipe leading, respectively, to and from the header, the primary pump being arranged to supply the header with lubricant and to remove the excess therefrom, the secondary pumps being arranged to take lubricant from the sight

feeds and deliver it to the discharge pipes, 10 and means for reciprocating the rods.

In testimony whereof I have signed my name to this specification in the presence of two subscribing witnesses.

LOUIS DUBRULLE.
